UNITED STATES PATENT OFFICE.

VICTOR H. EMERSON, OF NEW YORK, N. Y., ASSIGNEE TO EMERSON PHONOGRAPH COMPANY, INC., A CORPORATION OF NEW YORK.

TALKING-MACHINE.

1,273,342.

Specification of Letters Patent. Patented July 23, 1918.

Application filed February 18, 1916. Serial No. 79,217.

To all whom it may concern:

Be it known that I, VICTOR H. EMERSON, citizen of the United States, residing in the city, county, and State of New York, have 5 invented new and useful Improvements in Talking-Machines, of which the following is a specification.

My invention relates to phonographic devices and refers more particularly to means 10 for supporting sound-boxes in definite predetermined positions relative to the records with which they may be employed.

An object of my invention is to provide in talking machines simple, convenient and 15 effective means for adjustably holding the sound-box and its diaphragm in different positions relative to the grooves of sound records in reproducing from grooves of different types.

20 A further object of my invention is to provide for use in machines of the class described a swinging tone-arm, horn or other sound conducting and amplifying device with means for shifting the sound-box to different angles, rotatably upon the longitudinal axis of the tone-arm, not only that 25 the sound box mechanism may be adapted to records of different types, but that improved reproduction of sound may be obtained 30 therefrom.

At the present time there are in general 35 public use three types of record grooves, the first and oldest form, known as the vertically undulatory or Edison type of groove; the second, called the laterally undulatory or Berliner type, brought into public use at a somewhat later period than the 40 Edison design; and the third type, comprising a form of groove which has both lateral and vertical undulations. This last named type of sound reproducing groove known as the Emerson universal record, has only recently been introduced into public use for which Letters Patent were issued to 45 the present applicant.

In the Edison, or, as it is also called, the hill-and-dale type of groove the reproducing needle is adapted to vibrate within a vertical plane relative thereto as the point is 50 drawn over the up-and-down variations along the bottom of the groove. In the Berliner or zig-zag type of groove the needle at its point vibrates laterally within the horizontal plane of the surface of the record, 55 while in the third class, above referred to

as the Emerson type of grooves, the sound may be reproduced by vibrating the needle point either horizontally within or vertically to the surface plane of the record. Hence, in order to employ either an Edison 60 or a Berliner record a corresponding adjustment of the sound box and stylus is required for each, while with the Emerson universal record either adjustment applicable to the other respective types of record grooves 65 may be used to reproduce the sound represented thereby.

Accordingly various devices have been employed in the past, certain forms of which are still in use, for thus converting 70 the sound box from one position, in which it is operable for vertically undulatory grooves, to another adjusted position for grooves whose walls are laterally undulatory, in both of which adjustments the 75 diaphragm of the sound box and the stylus lever are swung through substantially ninety degrees from the one position to the other in order to conform to the differing characteristics of the respective grooves. 80 Hence, for the up-and-down groove the diaphragm in the sound box is almost universally held cross-wise of the groove, that is to say, either in a perpendicular or oblique plane that cuts the grooves at right angles 85 to the direction thereof; or, as in the earlier Edison and graphophone machines, the diaphragm was held in a plane substantially parallel to the surface of the record, or tangentially parallel with reference to 90 the point of contact of the stylus upon the cylindrical record used at that period. Likewise in connection with the Berliner zig-zag type of record groove the almost universal practice is to employ the vertical 95 arrangement of the diaphragm and stylus so that all parts vibrate laterally, as do the undulations of that type of groove. Thus it has heretofore been the prevailing practice that the point of the reproducing stylus 100 be so held as to vibrate either vertically for the Edison groove, or to oscillate laterally for the Berliner type.

In the present invention, however, while practising my invention with the Berliner 105 or zig-zag type of groove I use the diaphragm and stylus in the same general manner as now employed in connection with the laterally vibrating sound box, but when using my improvement with an Edison verti- 110

cally undulatory groove I support the sound box in a position not at all as has been the practice heretofore, but with the sound box inclined sidewise of and not crosswise to the course of the groove, so that while the sound box itself will vibrate laterally, as it does when used with the zig-zag groove, the point of the reproducing stylus will vibrate obliquely relatively to the surface of the record. It is not deemed necessary to specify in detail the reasons for the adjustments set forth, especially with reference to the vertically undulatory groove, inasmuch as I have pending before the Office an application for Letters Patent for improvements relative to sound box construction to be used in connection with the groove of that type, which application goes more fully into the description of that mechanism and the manner of its operation. Hence, in the present application it has been thought advisable to limit the specification to the convertible means entirely, whereby a sound box of the general type here described may be employed interchangeably with the one or the other types of grooves as described.

Briefly stated in its broad aspect, therefore, my invention comprises a tone arm with a sound box supported at one end and having means for holding the said box in two operable positions, one of which is adapted to reproducing sounds from the so-called vertically undulatory groove, the other adapted to operating in connection with a laterally undulatory groove; it being further provided that in both of said positions the needle point vibrates substantially in the same operable directions, although in connection with the latter or zigzag type of groove the vibrations of the stylus point are in a plane exactly parallel with the surface of the record when reproducing in the highest degree of efficiency, while in connection with the former or Edison type of groove the plane in which the stylus point oscillates is obliquely disposed with reference to the surface of the record to which it is thus applied. In connection with the Emerson type or universal record, which has vertical and lateral undulations combined in a single groove, my improvement will apply practically with the same effect in either of said adjusted positions as above distinguished.

Having reference to the drawings: Figure 1 in side elevation is a partial view of a tone conducting arm, mounted upon the frame of a talking machine, with a sound-box held vertically relative to the record in connection with which it is illustrated.

Fig. 2 is an end elevation of the sound-box and tone arm as shown in Fig. 1;

Figs. 3 and 4 are corresponding side and end views of the sound box and tone arm in a rotatably changed position relative to that shown in Figs. 1 and 2;

Fig. 5 is an enlarged partial view of the point of the needle resting in a record groove;

Figs. 6 and 7 are respective views of a tone arm and sound-box shown in comparative positions as in Figs. 1 and 3 respectively with the stylus lever moved;

Fig. 8 is a side elevation similar to Fig. 1 showing a horn attached directly to the sound box; and

Fig. 9 is a cross sectional view on line 9—9 of Fig. 8.

Referring to the drawings, illustrating a preferred embodiment of my invention employed in connection with a familiar form of sound-box 1, attached to the usual type of tone arm 6 as shown in Fig. 1, or to a horn 10^a as in Fig. 8, and having a straight vibrating lever 3 pivoted in the usual manner to the side of the box so as to operate in a plane substantially perpendicular to the diaphragm 2. Other types of sound-boxes, while conforming in the essential features to the structure described, may vary as to the relative arrangement of the stylus lever with reference to the diaphragm, or slight variations may be made in the direction of movement of the free or needle end 4 of the stylus lever relatively to the plane of the diaphragm; it will be noted, however, that in whatever form the sound-box is constructed and equipped, it has been found preferable to hold that member in certain predetermined positions to obtain the highest point of efficiency. That is to say, it is generally recognized that for reproducing from the Berliner or zigzag type of groove as already pointed out, the sound-box of the best construction has its lever disposed in a plane substantially parallel to that of the diaphragm and is held in an operable position so that the diaphragm and the stylus lever stand vertically with relation to the face of the record. The needle itself in this type of record may be slightly inclined within the vertical plane, as shown in Fig. 1, in which the contacting point of the needle has been advanced in the direction of the travel of the groove in which it rests. This variation is, however, of comparatively minor import and largely influenced by the nature of the contacting point of the reproducing needle, for if a sufficiently rounded ball point of sapphire or other hard material be employed, the needle may be held perpendicular to the zigzag groove as shown in Fig. 6 and reproduce to the highest degree of efficiency.

Heretofore the practice has been in adapting the sound-box diaphragm to co-act with a vertically undulatory record groove, to rotate said sound-box upon its axis parallel to the line of the groove through 90° starting from the vertical plane just described for operating in connection with the zig-zag

type of groove until parallel with the record surface, and then to incline the sound-box or the needle arm of the stylus lever at approximately 45° to the longitudinal lines of 5 the groove so as to permit the needle to vibrate vertically within the so-called vertically undulatory groove. In the position of the sound-box last above described as adapted to the vertically undulatory groove the 10 needle is held substantially in the position shown in Fig. 1, but the plane of the sound-box itself, as pointed out, would be modified to the extent of being rotated on the longitudinal axis of the needle through 90° from 15 the position shown in said Fig. 1 into a position that readily adapts itself to the vertical type of record as pointed out, but not shown in the drawings. The point of the vertically vibrating needle bears, in the form last 20 above described, it will be understood, directly upon the bottom of the groove and is operated entirely thereby and being held vertically in this manner both sides of the needle come into frictional contact equally 25 with the two sides of the groove as the needle point sinks into and rises from the depressions thereof. In my present invention, however, one side only of the needle 4 contacts the lateral wall of the vertically 30 undulatory groove, as shown in Figs. 4 and 5, the latter view having been somewhat enlarged in order to show more clearly the relative points of contact of the needle upon the respective groove surfaces.

35 Referring then to Figs. 4 and 5, more particularly to the latter, it would be seen that the needle has been tipped sufficiently to one side so that it may be caused to vibrate laterally along the undulations of the side 40 wall upon which it thus rests, in which inclined position it is held free from oppositely imposed impacts upon its other side which otherwise would be caused by the irregularities of the opposite wall of the 45 groove of this type.

50 While held in such slanted position the extreme point of the needle is elevated slightly above the bottom of the groove and travels in a line across the swells of the side 55 wall of the vertically undulating groove in the same manner as it would follow the sinuosity of the bottom of the groove if held upright, in consequence of which the sound reproducing vibrations are now transmitted to the diaphragm in a radically different manner than heretofore obtained. That is to say, in my improved mechanism the pivotal axis of the fulcrum of the stylus lever is disposed parallel to the direction of 60 the groove and hence permits the needle to vibrate laterally not only with relation to the groove but to the sound-box as well, which accordingly is now held within a plane parallel to that of the groove. The 65 point of the needle therefore as it follows

the undulations of the wall of the groove not only vibrates laterally and primarily, in transmitting those vibrations to the diaphragm in the usual manner, but also receives longitudinal or secondary vibrations 70 which are absolutely synchronous therewith and correspond in frequency and amplitude with the lateral principal vibratory actuations of the needle.

In this connection it remains to be pointed 75 out what action the needle 4 has when applied to the Emerson universal groove. That type of groove as described in my said pending application has undulations at the bottom and one side only, which side is 80 oblique, the other being smooth and vertically disposed relatively to the record. Hence the oblique side will engage the reproducing needle when in position illustrated in Figs. 4 and 5 in substantially the 85 same manner as shown in connection with the groove of those figures, excepting that the point will bear directly upon the vertical wall which is free from sinuosity.

The sound-box and vibrating stylus may 90 likewise be held vertically as shown in Figs. 1 and 2 and reproduce equally well when applied to the said Emerson type of groove so that in either adjustment my improved sound-box and tone arm would be applicable 95 to that form of sound record without further adjustment.

The angle at which the reproducing needle is inclined to the surface of the record, is, as 100 shown in Fig. 4, preferably established at substantially 45° when employed with the usual type of Edison groove, or with the so-called Emerson universal groove as now made. It is found, however, that satisfactory results may be obtained with either of 105 said grooves by varying the angle of inclination of the needle somewhat from that described; but the average declivity of the side wall of those types of grooves is approximately cut at that angle as nearly as may 110 be determined, and if the highest efficiency in reproducing therefrom be obtained, the needle should be held at a corresponding pitch with relation thereto.

115 The means employed for determining and controlling the relative positions of the sound-box 1 on the tone arm 10, or other supporting means, comprises in the form shown the elbow tube 6 as the throat of the sound-box, into which fits the end of the tone arm 10 proper, or horn 10^a, making a rotatable type of a telescopic joint between these members. A short circumferentially disposed slot 7 is provided in the tube 6 through which extends a stud or screw 8 120 to act as a guide and stop. The length of the slot is determined by the rotatable adjustment to be given the sound box and the stop pin 8 is placed in contact with one end 125 of the slot 7 when holding the sound box 130

in one of the desired positions, as is shown for example in Fig. 1 for reproducing from the zig-zag groove. Hence, when the tube 6 is carried to the position illustrated in Figs. 3 and 4 the stop 8 will be at the opposite end of the slot 7 as shown in Fig. 3. If the end of the tone arm 10 be fitted so as to form a frictional contact with the tube 6 the simple form of pin shown projecting into the slot would be sufficient to contact the rotatable adjustments described. But in connection with the preferred form of my improvement I employ a small thumb screw by means of which the tubes may be held more securely in the respective adjusted positions and may be employed similarly to thus maintain the parts in intermediate adjustments if desired, the head of the screw being brought into frictional engagement with the outer surface of the throat piece 6 for the purpose.

The tone arm of my improved construction is pivotally mounted to swing horizontally upon the post 14 that furnishes a socket bearing into which enters the pin 13 having attached thereto at its upper end a hinge 12 upon which pivotal bearing the swing arm may also be raised and lowered as desired.

While the preferred embodiment of my improvement comprises features substantially as set forth, I do not desire to be limited to the exact forms illustrated. For example any of the well known types of sound-box and forms of levers employed therewith may be used in the manner described. Likewise instead of the jointed construction of the tube 6 and tone arm 10, those parts may be made integral or relatively fixed and the entire arm and sound-box rotated together to the desired extent by any convenient means, such for example

as shown in Figs. 8 and 9 wherein a sound swivel pin 13^a is added to the hinge member 12^a (best shown in Fig. 9). Thus by 45 having the respective swivel pins 13 and 13^a correspondingly disposed with reference to the desired angle of inclination of the sound-box, whereupon the arm 10 or horn 10^a may be swung both vertically and 50 horizontally as required, the sound-box is thereby held in position contemplated by my improved means.

I claim—

A tone arm including two sections and a 55 swivel joint connecting the sections, one section consisting of an upper arm and a forearm, the forearm having its swinging end at an angle of substantially 90° to the axis of the joint, the upper arm and the 60 portion of the other section adjacent the swivel joint and the axis of the swivel joint being normally substantially horizontal, a sound box secured to the swinging end of the forearm so that the diaphragm and the 65 needle are in a plane substantially parallel to the axis of the swivel joint, and vertical in one position of the forearm whereby the device is adapted to play one type of record and may be rotated about the axis of the 70 swivel joint until the diaphragm and needle plane are substantially at forty-five degrees to the previous mentioned position so that the apparatus is also adapted to play another type of record. 75

In testimony whereof, I have signed my name to this specification in the presence of two subscribing witnesses, this 1st day of February, 1916.

VICTOR H. EMERSON.
